UNITED STATES PATENT OFFICE

92,661

DESIGN FOR A HAND MIRROR

William La Hodny and Gust C. Hoff, Buffalo,
N. Y., assignors to Standard Mirror Company,
Inc., Buffalo, N. Y., a corporation of New York

Application April 26, 1934, Serial No. 51,533

Term of patent 14 years

To all whom it may concern:

Be it known that we, WILLIAM LA HODNY and GUST C. HOFF, both citizens of the United States, and both residing at Buffalo, in the county of Erie and State of New York, have invented a new, original, and ornamental Design for a Hand Mirror, of which the following is a specification, reference being had to the accompanying drawing, forming part thereof.

The design consists of a mirror having a metal back which extends around the edge portion only of the mirror and a bifurcated handle extending

over the face of the mirror on one side and extending over the metal back on the other side.

In said drawing:

Figure 1 is a perspective view of the observance side of the hand mirror.

Fig. 2 is a perspective view of the reverse side of the hand mirror.

We claim:

The ornamental design for a hand mirror as shown and described.

WILLIAM LA HODNY.
GUST C. HOFF.
